UNITED STATES PATENT OFFICE.

CHARLES P. WILSON, OF CHICAGO, ILLINOIS, ASSIGNOR TO ROBERTS & SCHAEFER COMPANY, OF CHICAGO, ILLINOIS, A CORPORATION OF ILLINOIS.

MEASURING AND HOISTING APPARATUS.

1,363,029.

Specification of Letters Patent. Patented Dec. 21, 1920.

Application filed May 21, 1918. Serial No. 235,783.

To all whom it may concern:

Be it known that I, CHARLES P. WILSON, a citizen of the United States, residing at Chicago, in the county of Cook and State of Illinois, have invented a certain new and useful Improvement in Measuring and Hoisting Apparatus, of which the following is a specification.

My invention relates to improvements in coal handling devices, and has for one object to provide a new and improved form of device which when used in connection with a discharge hopper and a vertically reciprocating measuring and discharge bucket, will without any separate cradle, carriage or the like guide the bucket without rotating it from its vertical path over toward and convey it under the discharge mouth of the hopper in such manner that it will extend across that mouth and receive a predetermined quantity of coal or other similar material which quantity will be just sufficient to fill the bucket and thus insure proper measuring. In other words, my invention lies largely in a special arrangement of trackage, guides, and associated parts by the use of which I am enabled to move the bucket both vertically and horizontally and preferably without rotating it so as to place it under the discharge mouth of the bin. Other objects of the invention will appear from time to time in the specification, and I wish therefore, that my drawings be regarded as in a sense diagrammatic.

My invention is illustrated in one form in the accompanying drawings, wherein—

Figure 1 is a side elevation in part section showing the bucket at the lower end of its excursion;

Fig. 2 is a side elevation showing the bucket at the upper end of its excursion;

Fig. 3 is a front view of the bucket and associated parts;

Fig. 4 is a section along the line 4—4 of Fig. 1;

Fig. 5 is a section along the line 5—5 of Fig. 1.

Like parts are indicated by like characters in all the figures.

I have not illustrated the tower or the means for propelling the bucket, as the tower forms no part of my invention, and the same is true of the propelling means, but I have

illustrated a portion at both ends of the excursion of the bucket because that is important.

A is the usual type of receiving hopper crossed by the tracks A¹ which may support any suitable railroad car from which the coal will be dumped into the hopper. A² is a discharge spout or chute or port communicating with the bottom of the hopper and adapted to permit passage of solid or comminuted material such as coal and the like. A³ is a gate adapted to slide across the open end of the spout A² along a line normal to the path of travel of the material through the spout. It travels along rollers on track A⁴ and is normally held closed by the counterweight A⁵ and the hoisting rope A⁶.

B, B are two pairs of parallel vertically disposed tracks mounted on the tower or other suitable apparatus or structure upon which the whole system is supported. These parallel tracks guide the rollers B¹, B² on a bucket B² which bucket may be raised and lowered along the tracks by means of hoisting cable B⁴ controlled by mechanism not here shown or illustrated. This bucket is open above at B⁵ so that it may be filled, and is provided with the discharge opening B⁶ closed by a pivoted combined gate and chute B⁷. B⁸ is a single track parallel with the tracks B, B adapted to be engaged by the roller B⁹, which, when the bucket is intermediate the ends of its excursion by the engagement of the track B⁸, causes the gate to remain in the closed position and prevents discharge of material from the bucket.

C, C¹ are pairs of parallel opposed tracks. The pairs are parallel one with the other and are inclined to the tracks B. They pass downwardly under the hopper parallel with the outer end of the chute A². Each of the tracks C, C¹ has an upwardly curved extension C², C³ connecting with a vertical extension C⁴, C⁵ parallel with the track B and terminating in spread portions C⁶, C⁷. The track B terminates in a downwardly and sidewardly curved extension C⁸ cut away or notched as at C⁹ in line with the vertical portion of the track B.

The roller B¹ is long enough so that it overlaps the notched portions C⁹ and cannot pass through it as the bucket comes down,

but the roller B² is short enough so that it does pass through the notched portion, and therefore can assume the position shown in dotted lines in Fig. 1. As the bucket is lowered the roller B¹ therefore must follow the track portion C^s.

D, D¹ are rollers on the bucket B^a adapted to travel along the tracks C⁴, C², C, and C⁵, C³ and C¹ respectively. These rollers engage the upper vertically disposed portion of the tracks before the roller B² passes out of engagement with the track B. As the bucket travels down the roller B² assumes the position shown in dotted lines in Fig. 1. About that time the rollers D, D¹ pass on to the curved portion C², C³, and the bucket commences to move to the right while it goes down. While in this position with these tracks C³, C² out of parallelism, something must hold the bucket against rotation, and that something is the long roller B¹. It gives a three point triangular support for the bucket, and this three point triangular support operates until the bucket has got down so far that the rollers D, D¹ are held in the parallel portions C, C¹. Then you have a parallel motion apparatus and no rotation of the bucket is possible. About that time or a little thereafter, the roller B¹ passes out of engagement with the track C^s because the three point support is no longer needed. The bucket continues its downward and sideward path without rotation until the open portion B⁵ passes into register with the chute A² the roller B¹ does not engage the track C¹ after leaving the track C^s and when the parts are returned on the upward excursion it simply enters the lower spread mouth of the track C^s. The rollers D¹, D¹ extend farther out than the rollers B¹, B¹ hence they contact the track which is not engaged by the rollers B¹, B¹.

As the bucket continues its downward and sideward motion, that is its inclined path, it first engages, of course, the door or gate and forces that down against the counterweight and the door immediately opens and coal gradually runs into the bucket and fills it. It fills the bucket but none overflows, of course, and as soon as the bucket is filled a pull on the cable will pull the bucket back up along the inclined tracks until it engages the vertical tracks and then it will come on up to where it is to be dumped. As it is pulled up it brings with it the door finally closing off the flow and cutting across the column of coal leaving everything ready for the next load.

The gate B⁷ except when the bucket is being dumped is in the closed position as shown in Fig. 1. It will be held in such position by a sliding latch E. This latch E takes the form of a pin slidable in brackets E¹, E¹ adapted to drop down under the weight of gravity and come in front of the

upper lip of the gate B⁷ to hold it closed. This pin is heavy and gravity alone is sufficient to hold it down but to make assurance doubly sure, a spring E² assists the force of gravity though the primary purpose of the spring is to prevent rattling of the parts. E³ is a pin on the latch E. It is adapted to be engaged by a lever E⁴ pivoted on the axis of the roller D and rigid with a control lever E⁵ having at its end a roller E⁶. This roller E⁶ is adapted normally to be held by the weight of the latch and spring in the upper outer position shown in Fig. 1, but as the bucket approaches the upper end of its excursion this roller will be engaged by a cam rack E⁷ which has first an engaging part E⁸, then an inclined part E⁹ which causes the roller to assume the position in Fig. 2 and then a holding part E¹⁰ which holds the roller there. As the bucket comes up the lever is thus rotated to raise the latch and the gate would open were it not for the track B⁸, but after the bucket has been raised beyond a predetermined point the roller B⁹ rides out on the off set end of the track B⁸ and the bucket can dump. If it should happen that the bucket went up too far, the link E¹¹ would come into play to limit the rotation of the gate B⁷ so that it would not get down behind the track B⁸ in a reverse position.

It will be understood that the roller E⁶ is in engagement with the track E⁷ and with that track only. The roller does nothing except when it is about to trip the latch and it will be further noted that the arrangement of the parts is such that the track B⁸ will always have closed the door on the return before the latch is released. This track B⁸ may continue down as shown in Fig. 1, but in most cases it will be omitted as the latch itself is a positive one and it is only necessary to have the track in place where the latch is released.

I have not illustrated or described the means for operating the gate as a result of the movement of the bucket to cause discharge of coal from the hopper into the bucket because that may take any desired form and it is no essential part of my invention. It will be evident that many changes may be made both in size, shape, and arrangement of parts and that while the device as I have shown it is operative it should be regarded as in a sense diagrammatic as showing one of many mechanical arrangements and falling under the scope of my claims.

The use and operation of my invention are as follows:

Goal is first supplied to the large hopper in any suitable manner, the discharge gate from the hopper being, of course, closed. The machinery for reciprocating the bucket along the tracks is then put into operation.

- At the lower end of its excursion it will be guided from the vertical tracks around the curve or changed in direction from the vertical to the inclined by the three-point support on the curved track arrangement and it will then continue its descent until it comes in register with the hopper chute, meanwhile opening the gate to permit outflow of the coal. Because the bucket is in register with the gate and so arranged that the pressure of coal flowing out through the port from the hopper cannot force coal out of the bucket, it will be evident that the quantity of coal can be measured if you know the capacity of the bucket. That, of course, is known and so a predetermined amount of coal will be taken up at each excursion of the bucket. When the bucket is filled it will start up, closing the gate as it goes. Soon after leaving the gate it will pass around the curved track arrangement onto the vertical track and will travel until it reaches the point where the latch will be released as indicated, the dumping track will rest against the track when the gate will be allowed to open and the bucket will be dumped. Then as the bucket comes down the dumping gate will be closed, the latch released and then the bucket with its latched and closed gate will pass down to repeat the process.
- A great deal of importance must be attached to the arrangement for guiding the bucket under the hopper so that it may be filled from that hopper without the insertion of any separate measuring device. It will be noted that no separate apparatus is used, that tracks are provided which engage rollers on the bucket and carry it down. The parallel arrangement of the two closed tracks with the rollers engaging them make sure that the bucket will go forward without tilting once the change in direction has been made, but while change in direction is being made the curved tracks are a source of danger which is obviated by using the laterally deflected lower portion of the main vertical track and the pin on the bucket which travels therealong.
- I claim:—
1. A coal handling plant comprising a ported receiving hopper, a vertically disposed hoisting track curved at its lower end toward the hopper, a plurality of vertical guide tracks parallel with the hoisting track and projecting above the lower end thereof, said tracks being curved toward the hopper adjacent the curved hoisting track extension and terminating in parallel tracks inclined beneath the hopper, a bucket, means for hoisting it and members projecting therefrom and engaging the hoisting track, and the guiding tracks, one of the members arranged for engagement of the hoisting track being adapted to remain in engagement with the curved extension as the bucket descends.
  2. A coal handling plant comprising a receiving hopper having a discharge port, a hoisting and measuring bucket, a vertical hoisting track along which it travels, inclined guide tracks adapted to guide it beneath the hopper, means associated with said tracks for holding the bucket against rotation while traveling along them and additional means interposed between said tracks for holding the bucket against rotation while moving from one to the other group of tracks.
  3. The combination with a hopper having a discharge port and a hoisting and measuring bucket adapted to take material therefrom of a vertical track leading upwardly from the hopper, a pair of parallel inclined tracks beneath the hopper and members on the bucket adapted to engage such tracks and means for guiding the bucket as it moves from the vertical to the inclined tracks, said means comprising a curved extension in continuation of the vertical track adapted to guide one of the track engaging means over toward the hopper and to remain in contact with the bucket until the bucket is well on its way on the inclined tracks.
  4. A coal handling plant comprising a hopper having a discharge port, a bucket having an inlet port, said ports in planes substantially parallel with each other when in register, means for moving the bucket vertically, means for moving it laterally beneath the hopper at the lower end of its excursion so as to bring the two ports into register, said means comprising two laterally deflected tracks and projections on the bucket which ride on said tracks, and a cut-off gate between and substantially parallel with the ports and adapted to be moved by the bucket and to leave a free passage from the hopper to the bucket while the ports are in register.
  5. A coal handling plant comprising a hopper having a discharge port, a bucket having an inlet port, said ports in planes substantially parallel with each other when in register, means for moving the bucket vertically, means for moving it laterally beneath the hopper at the lower end of its excursion so as to bring the two ports into register, said means comprising two laterally deflected tracks and projections on the bucket which ride on said tracks, and a cut-off gate between and substantially parallel with the ports and adapted to be moved by the bucket and to leave a free passage from the hopper to the bucket while the ports are in register, and means for normally holding the gate closed against the action of the bucket.
  6. A coal handling plant comprising a

1. A coal handling plant comprising a hopper having a discharge port, said ports in planes substantially parallel with each other when in register, a bucket having an inlet port, vertical tracks and projections on the bucket engaging said tracks, means for moving the bucket laterally beneath the hopper at the lower end of its excursion so as to bring the two ports into register, said means comprising laterally deflected tracks and projections on the buckets to engage them and a cut-off gate beneath and substantially parallel with the ports and adapted to be moved by the bucket and in engagement with it and to leave a free passage from the hopper to the bucket while the ports are in register. 65
2. A coal handling plant comprising a hopper having a discharge port, a bucket having an inlet port, vertical tracks and projections on the bucket engaging said tracks, means for moving the bucket laterally beneath the hopper at the lower end of its excursion so as to bring the two ports into register, said means comprising laterally deflected tracks and projections on the buckets to engage them and a cut-off gate adapted to move in response to the bucket movement and to leave a free passage from the hopper to the bucket while the ports are in register, and means for steadyng the bucket as it passes from the vertical to the laterally deflected tracks. 70
3. A coal handling plant comprising a hopper having a discharge port, a bucket having an inlet port, vertical tracks and projections on the bucket engaging said tracks, means for moving the bucket laterally beneath the hopper at the lower end of its excursion so as to bring the two ports into register, said means comprising laterally deflected tracks and projections on the buckets to engage them and a cut-off gate adapted to move in response to the bucket movement and to leave a free passage from the hopper to the bucket while the ports are in register, and means for steadyng the bucket as it passes from the vertical to the laterally deflected tracks. 75
4. A coal handling plant comprising a hopper having a discharge port, a bucket having an inlet port, vertical tracks and projections on the bucket engaging said tracks, means for moving the bucket laterally beneath the hopper at the lower end of its excursion so as to bring the two ports into register, said means comprising laterally deflected tracks and projections on the buckets to engage them and a cut-off gate adapted to move in response to the bucket movement and to leave a free passage from the hopper to the bucket while the ports are in register. 80
5. A coal handling plant comprising a hopper having a discharge port, a bucket having an inlet port, vertical tracks and projections on the bucket engaging said tracks, means for moving the bucket laterally beneath the hopper at the lower end of its excursion so as to bring the two ports into register, said means comprising one or more pairs of double tracks having vertical upper portions parallel in part to the main vertical track, divergent upper ends and laterally deflected lower portions and projections on the buckets to engage them and a cut-off gate adapted to move in response to the bucket movement and in engagement with it and to leave a free passage from the hopper to the bucket while the ports are in register. 85
6. A coal handling plant comprising a hopper having a discharge port, a bucket having an inlet port, vertical tracks and projections on the bucket engaging said tracks, means for moving the bucket laterally beneath the hopper at the lower end of its excursion so as to bring the two ports into register, said means comprising laterally deflected tracks and projections on the buckets to engage them and a cut-off gate adapted to move in response to the bucket movement and to leave a free passage from the hopper to the bucket while the ports are in register. 90
7. A conveying bucket and means for moving it vertically, in combination with a hinged dumping door on the bucket, a latch for the same comprising a vertically moving pin mounted on the bucket and adapted to overhang the door and thus hold it closed, in combination with means for lifting such vertically moving latch out of engagement with the bucket door responsive to the vertical travel of the bucket. 95
8. A conveying bucket and means for moving it vertically, in combination with a hinged dumping door on the bucket, a latch for the same comprising a vertically moving pin mounted on the bucket and adapted to overhang the door and thus hold it closed, in combination with means for lifting such vertically moving latch out of engagement with the bucket door responsive to the vertical travel of the bucket, and a spring to normally hold the latch in door locking position. 100
9. A conveying bucket and means for moving it vertically, in combination with a hinged dumping door on the bucket, a latch for the same comprising a vertically moving pin mounted on the bucket and adapted to overhang the door and thus hold it closed, in combination with means for lifting such vertically moving latch out of engagement with the bucket door responsive to the vertical travel of the bucket, and a spring to normally hold the latch in door locking position. 105
10. A conveying bucket and means for moving it vertically, in combination with a hinged dumping door on the bucket, a latch for the same comprising a vertically moving pin mounted on the bucket and adapted to overhang the door and thus hold it closed, in combination with means for lifting such vertically moving latch out of engagement with the bucket door responsive to the vertical travel of the bucket, and a spring to normally hold the latch in door locking position. 110
11. A conveying bucket and means for moving it vertically, in combination with a hinged dumping door on the bucket, a latch for the same comprising a vertically moving pin mounted on the bucket and adapted to overhang the door and thus hold it closed, in combination with means for lifting such vertically moving latch out of engagement with the bucket door responsive to the vertical travel of the bucket, and a spring to normally hold the latch in door locking position. 115
12. A conveying bucket and means for moving it vertically, in combination with a hinged dumping door on the bucket, a latch for the same comprising a vertically moving pin mounted on the bucket and adapted to overhang the door and thus hold it closed, in combination with means for lifting such vertically moving latch out of engagement with the bucket door responsive to the vertical travel of the bucket, and a spring to normally hold the latch in door locking position. 120
13. A conveyer bucket and means for moving it in combination with a dumping door, latching means to hold said door normally closed, means for releasing the latch and permitting the door to open responsive to the vertical movement of the bucket and a supplementary door support which limits the opening motion of the door, consisting of a link pivoted to the bucket and provided with a slot and a pin which passes through the slot and is attached to the door.
